(57) **CLAIM**

We claim the ornamental design for a mouse, as shown and described.

DESCRIPTION

FIG. 1 is a rear perspective view of a mouse showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a rear perspective view of another mouse showing my new design;

FIG. 8 is a front view of the mouse of FIG. 7;

FIG. 9 is a rear view of the mouse of FIG. 7;

FIG. 10 is a left side view of the mouse of FIG. 7;

FIG. 11 is a right side view of the mouse of FIG. 7;

FIG. 12 is a top view of the mouse of FIG. 7;

FIG. 13 is a rear perspective view of another mouse showing my new design;

FIG. 14 is a front view of the mouse of FIG. 13;

FIG. 15 is a rear view of the mouse of FIG. 13;

FIG. 16 is a left side view of the mouse on FIG. 13;

FIG. 17 is a right side view of the mouse on FIG. 13; and,

FIG. 18 is a top view of the mouse of FIG. 13.

The broken lines in the drawings are for illustrative purposes only and form no part of the claimed design. The short dash long dash lines are boundary lines and form no part of the claimed design.
